Primary Examiner — Austin Murphy(74) *Attorney, Agent, or Firm* — Michael Best & Friedrich LLP(57) **CLAIM**

The ornamental design for a drying rack peg, as shown and described.

DESCRIPTION

FIG. 1 is a front perspective view of a drying rack peg showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate unclaimed portions of the drying rack peg and form no part of the claimed design.

1 Claim, 6 Drawing Sheets(56)
